UNITED STATES PATENT OFFICE.

HERBERT PEARCE, OF BROADHEATH, ALTRINCHAM, ENGLAND, ASSIGNOR TO LINOTYPE AND MACHINERY LIMITED, OF LONDON, ENGLAND, A COMPANY.

KEYBOARD MECHANISM OF TYPOGRAPHIC MACHINES.

941,383.

Specification of Letters Patent. Patented Nov. 30, 1909.

Application filed September 14, 1907. Serial No. 392,867.

to all whom it may concern:

Be it known that I, HERBERT PEARCE, a subject of the King of the United Kingdom of Great Britain and Ireland, and residing 5 at the Linotype and Machinery Works, Broadheath, Altrincham, in the county of Chester, England, have invented new and useful Improvements in the Keyboard Mechanism of Typographic Machines, of which 10 the following is a specification.

This invention relates to improvements in the keyboard mechanism of typographic machines as that mechanism is described for example in the specifications of Letters Patent 15 530,931, 531,266, and 554,842. Each of the mechanisms of these three patents has all the cam levers or carriages of each series pivoted upon a single rod. When therefore it becomes necessary to take any of either 20 series of cam levers out of the machine, the respective rod must be withdrawn for a longer or shorter distance according to the position of the said lever, lengthwise of its series, and be afterward replaced.

25 The object of the present invention is to dispense with the two pivot rods and to provide independent journals and bearings for each cam lever in such a way that any one of them can be taken out of the machine 30 and either replaced or substituted quickly and easily without disturbing any of the other cam levers.

In the accompanying drawings which are 35 to be taken as part of this specification and read therewith:—Figure 1 is a transverse section of as much of the keyboard mechanism, as is necessary for illustrating the present invention; Fig. 2 is a rear elevation, and Fig. 3, a plan of part of such mechanism; Fig. 4 is an elevation of a detached portion thereof, and Fig. 5 is a plan of one of the cam levers, with its cam pivoted therein.

In carrying the invention into effect, each 45 cam lever 1, as shown best in Fig. 5, has its own axle 2 incorporated with it. The fixed vertical plate 3 which, in typographic machines as ordinarily constructed, has generally provided or supported the bearings for 50 its series of cam levers, is, according to the present invention, slotted or grooved in both directions, that is, transversely of its length as at 4, to receive the levers themselves, and longitudinally as at 5, to receive the axles 55 2, the slot 5 appertaining to each half of

such axles being preferably separated by a web or partition 6 from the slot appertaining to the next adjacent half axle, as seen best in the broken away part of Fig. 3. When the series of levers 1 are in working 60 position, they, or some portion of them, project above the top of the fixed vertical plate 3. A cap plate 7 notched as at 8 across its bottom edge, see particularly Fig. 4, fits down upon the fixed vertical plate 3, its 65 notches 8 standing over the respective levers 1, as shown best in Fig. 2.

The cap plates 7 are each held in their effective position by two spring catches 9, one bearing on each of its ends, and both 70 secured as by screws 10 to the respective ends of the respective cam carriage frame 11. The spring catches 9 shown in the drawings are each formed of two parts secured together by screws 12, one part substantially horizontal and the other part substantially vertical, the downwardly extending portions of the said catches terminating in rounded ends which are adapted to engage with correspondingly shaped recesses 75 13 in the respective cap plate 7.

In the right-hand part of Fig. 1, that is to say, to the right of the escapement rod 14, and in Figs. 2 and 3 the cam levers or carriages 1 are shown in their working condition, their axles 2 being held down in the slots 5 by the cap plate 7, which, in turn, is held in position by the spring catches 9. At the left-hand side of the escapement rod 14 in Fig. 1, there is shown the manner in 90 which a cam lever 1 and its cam are removed from the machine, one such device being represented as partly withdrawn, for which purpose the appropriate cap plate 7 had previously been removed after the respective 95 catches 9 had been released from the recesses 13.

It is to be observed as a matter of considerable importance that the above-described removal of a cam lever or carriage, is effected without, in any way disturbing any 100 of the other cam levers or carriages.

The parts of the mechanism which are represented in the drawings but which have not been hereinbefore referred to, form no 105 part of the present invention, and therefore call for no special description.

I claim,

1. In the keyboard mechanism of a typographic machine the combination with cam 110

- carriages adapted to be released by the operation of the key levers, of an axle for each cam carriage independent of the axle of any other of such cam carriages and about the axis of which first named axle the said carriage is adapted to turn, a bearing for each axle, and retaining means adapted to prevent the escape of an axle from its bearing.
- 10 2. In the keyboard mechanism of a typographic machine the combination with cam carriages adapted to be released by the operation of the key levers and an axle for each cam carriage independent of the axle of any other of such cam carriages and about the axis of which first named axle the said carriage is adapted to turn, of a plate having slots or grooves adapted to receive the axles of the cam carriages, and a cap adapted to prevent the escape of said axles from said slots or grooves.
- 15 3. In the keyboard mechanism of a typographic machine the combination with cam carriages adapted to be released by the operation of the key levers, an axle for each cam carriage independent of the axle of any
- 20
- 25

other of such cam carriages and a plate having slots or grooves adapted to receive the axles of the cam carriages, of a removable cap plate adapted to retain the axles in the 30 said slots or grooves.

4. In the keyboard mechanism of a typographic machine the combination of cam carriages adapted to be released by the operation of the key levers, an axle for each cam carriage independent of the axle of any other of such cam carriages and about the axis of which first named axle the said carriage is adapted to turn, a plate having slots or grooves adapted to receive the axles of 35 the cam carriages, webs or partitions separating adjacent slots or grooves from each other, and retaining means adapted to prevent the escape of said axles from said slots or grooves.

In witness whereof I have hereunto set my hand in the presence of two witnesses.

HERBERT PEARCE.
